McGraw & McCready.

UNITED STATES PATENT OFFICE.

FREDERICK M. FURBER, OF REVERE, MASSACHUSETTS.

SPARK-PLUG.

1,323,360.

Specification of Letters Patent.

Patented Dec. 2, 1919.

Application filed January 21, 1918. Serial No. 213,021.

To all whom it may concern:

Be it known that I, FREDERICK M. FURBER, a citizen of the United States, residing at Revere, in the county of Suffolk and State 5 of Massachusetts, have invented certain Improvements in Spark-Plugs, of which the following description, in connection with the accompanying drawings, is a specification, like reference characters on the drawings indicating like parts in the several figures.

Spark plugs of the type commonly used in internal combustion engines comprise a metallic shell constructed to be threaded into an aperture in the engine cylinder, an 15 insulator mounted in said shell and a pair of electrodes electrically separated by the insulator. The most serious problem in the manufacture of devices of this kind concerns the mounting of the insulator in the shell. 20 These insulators usually are made of porcelain so that they are relatively fragile and the usual commercial constructions and methods of manufacture are open to the objection that they break a substantial percentage 25 of the insulators during the process of manufacture and that they frequently result in mounting the insulator in such a manner that it is under internal strains that cause it to break very easily while in use, either 30 due to a relatively light blow which it should be able to successfully withstand, or due to strains set up by changes in temperatures to which it is subjected while in use.

A further problem involving the mounting of the insulator in the shell to which attention has been especially directed by the trade in recent times is that of making the plug gas tight. Insulators whether made of porcelain or other materials are not absolutely uniform in shape and dimensions, and this is particularly true of porcelain insulators because they tend to warp in the baking operations. Consequently, it is difficult to mount these insulators in their shells by any 45 methods capable of adoption in commercial manufacture so that they will be absolutely gas tight when subjected to the high pressure conditions and the wide range of temperatures which they have to withstand in 50 actual use.

The present invention is concerned particularly with the problems just described and it aims to devise a spark plug construction that will solve these difficulties.

55 The invention will be readily understood from the following description, when read

in connection with the accompanying drawings, and the novel features will be particularly pointed out in the appended claims.

Referring now to the accompanying drawings,

Figure 1 is a view in side elevation of a spark plug embodying this invention;

Fig. 2 is a central, vertical, cross sectional view showing the spark plug of Fig. 1 65 mounted in an engine cylinder;

Fig. 3 is a vertical, cross sectional view of part of the spark plug showing one step in its process of manufacture; and

Figs. 4, 5 and 6 are side views of different 70 constructions of shell parts used with a given body to make different sizes of spark plugs.

The construction shown comprises a shell 75 consisting of a body 2 and a sleeve 4. The body may be made out of hexagonal bar stock by turning off a part of the material from a piece of the required length to form a cylindrical skirt 6, leaving the upper part in its original hexagonal form so that a 80 wrench may be conveniently applied thereto to screw the plug into or out of an engine cylinder. The piece of stock is then bored, provided solid stock is used, and is counter-bored for a distance from its lower or inner 85 end so as to leave a flange 8 projecting inwardly at the upper end of the body 2.

The insulator used preferably is of substantially the form shown and consists of a central enlargement or body portion of substantially cylindrical form, and provided with reduced upper and lower extensions 12 and 14, respectively, preferably tapering somewhat and projecting from the opposite ends of the central portion 10. Beveled or 90 frusto-conical shoulders 16 and 18, respectively, are formed at the upper and lower ends, respectively, of the body 10.

The insulator is clamped in the shell by parts that engage the shoulders 16 and 18. 100 The flange 8 forms a seat for the upper shoulders 16 and the upper end of the sleeve 4 is shaped to engage the lower shoulders 18. Instead of having these parts engage directly the shoulders of the insulator it is 105 preferable to interpose gaskets 20 and 22 between the upper and lower shoulders and the parts that exert clamping pressure on them. I prefer to use a solid metal washer at 20 made, for instance, out of copper or a 110 suitable composition, and a gasket of the copper asbestos type, very commonly used.

in these devices, at 22. The pressure required to clamp the insulator securely in the body is produced by threading the sleeve 4 into the lower end of the body 2. For this purpose the sleeve is provided with a head *a* larger in diameter than the shank *b* which is threaded into the cap 24 of the engine cylinder 26. A relatively fine thread, preferably of the buttress type, is used, as shown in the drawings, and is cut left handed.

In assembling the plug, the body 2 may be placed in its inverted position in a fixture 28 having a hexagonal socket to fit the outer surface of the body 2. The gasket 20 may then be dropped into the body. The insulator next is set into the body and a gasket 22 is placed on the lower shoulder of the insulator. While the parts are in this position the sleeve 4 is threaded into the lower end of the body, a suitable wrench shaped to fit the threaded shank *b* of the sleeve and constructed to clamp this shank being used for this purpose. The wrench shown comprises an internally threaded collar 30 adapted to be threaded on to the shank *b* of the sleeve, this threaded portion being split longitudinally and tapered externally to fit an internally tapered portion of the body 32 of the wrench. The parts 30 and 32 are threaded together so that as the wrench is turned to thread the sleeve into the body 2, the bushing 30 will be caused to grip the shank *b* very securely but will not injure the threads. A very long handle may be used on the wrench, or the sleeve may be threaded in by power mechanism, but sufficient force should be applied to the sleeve to cause it to exert a very heavy pressure, say 4,000 or 5,000 pounds on the lower shoulder of the insulator. This pressure distorts the gaskets 20 and 22 until they accurately fit the space between the insulator shoulders and the members that bear against them. The gasket 22 becomes seated on the lower shoulder 18 long before the pressure of the sleeve reaches its maximum and thereafter the sleeve slides on the gasket but the gasket does not move with reference to the insulator. I find that this method of assembling produces an exceedingly tight joint at both shoulders of the insulator, the joint at the lower shoulder being exceptionally good. By using a buttress thread, as shown in the drawings, any danger of splitting the lower end of the shell, which might be produced if a V-shaped thread were used, is avoided.

The construction of sleeve shown provides a shoulder 34 between the shank *b* and the head *a*. It is desirable to have this shoulder substantially flush with the lower end of the body 2 so that when the plug is in its normal position in the engine, as shown in Fig. 2, any leakage of the gas along the thread of the portion *b* may be prevented by placing

a gasket 36 between this shoulder and the cylinder cap 24, as shown in said figure. Accordingly, after the insulator has been clamped in the manner above described an end milling tool is brought down on the lower end of the body 2 and cuts down this body until it is flush with the shoulder 30.

This construction provides a very satisfactory form of spark plug and one which substantially overcomes the objections hereinbefore described. The shell parts 2 and 4 may be made automatically in screw machines or turret lathes and may be assembled very easily and without the use of skilled labor. The percentage of leaky plugs is exceedingly small since there is practically always a gas tight joint at the bottom shoulder of the insulator and in a very high percentage of the plugs the joint at the upper shoulder also is gas tight. By making the shoulder 30 flush with the lower end of the body 2, and using a gasket 36 underneath these shoulders as shown in Fig. 2, any attempt of the gas to creep along the thread on the shank of the plug is avoided. The pressure of the shoulder 30 on the gasket 36 also prevents gas that works along the thread of the shank *b* from continuing its travel along the thread between the head of the sleeve 4 and the body 2 where it would find access to the space above the gasket 22 and would escape at the upper end of the plug if the joint between the shoulder 16 and the flange 8 happened to be leaky. This construction also prevents gas that might find its way past the gasket 22, in the same event of a leak at this joint, from traveling along the thread between the parts *a* and 2 and escaping at the shoulder 34.

The use of a left hand thread between the head of the sleeve 4 and the bottom of the body 2 is an important feature. The plug usually is turned into an engine cylinder by means of an ordinary wrench. While the force exerted on the body 2 would tend to unscrew it from the sleeve, this force would be much too small to produce the slightest danger of starting the thread and thus relieving the pressure that clamps the insulator in its normal position. These plugs frequently "freeze" in a cylinder and in attempting to get them out the workman may have to use a heavy hammer on the wrench that he applies to the body 2, and if the body and sleeve were united by a right hand thread there would be considerable danger of starting this thread in attempting to remove the spark plug in this manner. It will be seen, however, that by using a left hand thread between the parts 2 and 4 the force exerted in unscrewing the plug from the cylinder, will tend to turn the sleeve 4 all the tighter into the body 2 and thus tend to increase the pressure exerted by these parts on the insulator.

Since a much longer handled wrench is used in threading the sleeve into the body than is ever used in threading the plug into an engine cylinder, and since the thread between the head of the sleeve and the body is much finer than the thread on the shank of the sleeve, there is not the slightest danger of starting the thread between the sleeve and the body while the plug is in use. In fact, these parts are secured together so firmly that they rarely can be separated even when a deliberate effort is made to do so without the use of special tools.

This construction also is very convenient from a manufacturing standpoint since a standard body and insulator may be used for all of the more important commercial sizes of spark plugs. It is merely necessary to change the dimensions of the shank portions b of the sleeve 2 and change the thread on this portion in order to adapt the plug to any one of a variety of sizes. Figs. 4, 5 and 6 show three different styles of sleeve which could be used in the body 2 shown in Fig. 2. That is, the heads a of all these sleeves are of the same diameters and have the same thread cut on them. The shanks b , however, are all different. In Fig. 4, the shank is a seven-eighths inch standard thread, in Fig. 5, a metric thread, and in Fig. 6, a one-half inch pipe thread. These three are the most common commercial sizes.

While I have herein shown and described the best embodiment of the invention of which I am at present aware, it is obvious that this embodiment may be modified in certain details of construction while still retaining the essential principles and characteristics of the invention. The invention therefore is not limited to embodiment in the precise form shown.

What I claim as new, is:

1. A spark plug comprising a body constructed to receive a wrench, a sleeve having a left hand threaded part screwed into the lower end of said body and a right hand

threaded part projecting below said body and adapted for engagement with an engine cylinder, and an insulator secured in said body by said sleeve.

50

2. A spark plug, comprising a hollow body having an inwardly projecting flange at its upper end and having a left hand thread formed in the lower portion of the bore thereof, a sleeve having a head in threaded engagement with said body and threaded for engagement with an engine cylinder, an insulator having upper and lower shoulders clamped between said flange and the upper end of said sleeve, and gaskets interposed between said shoulders and the respective parts in clamping engagement with them.

60

3. A spark plug, comprising a body, a sleeve, said sleeve and body having left hand threaded portions in engagement with each other by means of which they are secured together, and an insulator secured in said body by said sleeve, said sleeve having a right hand threaded portion projecting below said body and adapted to be threaded into an engine cylinder.

65

4. A spark plug comprising a body constructed to receive a wrench whereby the plug may be screwed into or out of an engine cylinder, a sleeve, said sleeve and body having cooperating left hand threaded portions in engagement with each other by means of which they are secured together, and an insulator mounted in said body and having an enlargement with upper and lower shoulders at the opposite ends of said enlargement, said body and sleeve being provided with parts constructed to engage said shoulders and thereby clamp said insulator in its operative position in said body, and said sleeve having a shank portion threaded for engagement with an engine cylinder.

75

In testimony whereof I have signed my name to this specification.

FREDERICK M. FURBER.
